STOP MECHANISM.

1,182,017.

Specification of Letters Patent.

Patented May 9, 1916.

Application filed February 4, 1914. Serial No. 816,433.

To all whom it may concern:

Be it known that we, JOHN KIEWICZ and FRANK ZALESKI, citizen of the United States of America, and subject of the German Emperor, respectively, residing at Hyde Park, in Norfolk county, and at Cambridge, in the county of Middlesex, respectively, State of Massachusetts, have invented certain new and useful Improvements in Stop Mechanisms, of which the following is a specification, reference being had therein to the accompanying drawing.

This invention relates to stop mechanisms and more particularly to a mechanical contrivance associated with the driving mechanisms of machines of various sorts for effecting the stoppage thereof in a desirable manner.

An object hereof is to afford an efficient and durable stop mechanism adapted to employment with light, fast-rotating machines such as sewing machines, power driven from a continuously rotating shaft.

Another object is to provide a stop mechanism which is easily controlled and operated and serves to promptly, yet without shock, bring the main shaft of the machine to rest preferably with the needles or other operating parts of the machine at a predetermined point in the cycle of their operations.

Other objects hereof will be perceived from the hereinafter following description of an illustrative mechanism embodying the principles of this invention.

To the attainment of the objects referred to the present invention consists in the novel combinations, arrangements, mechanisms, devices, details and other features illustrated or described herein.

Figure 1 is a front elevation partly in section of a portion of a machine embodying a stop mechanism constructed on the principles of this invention, the base or frame being shown in section on the plane 1-1 of Fig. 2. Fig. 2 is a bottom plan view of the parts shown in Fig. 1. Fig. 3 is a right elevation of the same. Fig. 4, on an enlarged scale, shows a detail. Fig. 5 is transverse section on the plane 5-5 of Fig. 1, showing the brake drum. Fig. 6 is a rear elevation of the parts in Fig. 5, the drum partly broken away. Fig. 7 is a transverse section on the plane 7-7 of Fig. 1, showing both the drum and brake band.

The same reference numerals designate corresponding parts in the several views of the drawings.

For convenience of illustration, the general type of sewing machine, illustrated in prior Patent No. 1,047,537 of December 17th, 1912, has been selected and such prior patent may be referred to for the general operation of such a machine and for various details not constituting *per se* the present invention.

The hollow base 9 of the machine supports the stitching mechanism, which would be at the left end of the machine and for convenience is omitted, and the driving and stop mechanism which is at the right end, partly within and partly without the base. The main shaft 10 extends from the driving mechanism to the stitching mechanism and operates the needles and coöperating parts.

A presser-foot 11 is shown in Fig. 3 carried at the forward end of the arm 12 of a swinging lever the shaft 13 of which affords a pivotal bearing and also carries a second or actuating arm 14 extending within the base 10. The arm 14 has at its extremity a stud 15 to permit the lifting of the presser-foot, against spring 16, by a lifting part or swinging arm 17, which is held down by spring 18 so that its stud 19 bears on a device or cam 20 on main shaft 10 as shown. Thereby the presser-foot is raised automatically when the machine is stopped. When the machine is started the arm 17 is shifted to the left, so that cam 20 will not lift the presser-foot, by means later described.

The main shaft is supported in bearings, one of which, 21, is shown, and the shaft extends from the interior of the base through its right hand wall to the exterior parts.

Referring now more particularly to the driving and stop mechanism, it involves a brake device associated with the rotary shaft 10 or preferably with a drum constituting substantially an enlarged portion of the shaft, together with contacts or lugs upon the shaft and the brake device respectively and means for relatively adjusting the contacts endwise; namely, by bodily adjusting the entire brake device relatively endwise so as to bring the contacts into or out of registry. By endwise in this connection is always meant longitudinal of the main shaft or substantially parallel therewith. The brake device

preferably comprises a brake shoe in the form of a band extending nearly around the drum, and the contact for operating the brake band is directly upon it, so that, when the brake band is shifted endwise, its contact is brought into alignment with the shaft or drum contact so that the braking force is applied by the machine's momentum to effect the stoppage. The drum contact being carried in a resiliently yielding manner prevents shock and effects the application of the braking force progressively. With the described parts is combined a power uncoupler in the nature of a belt shifter which 15 may shift a belt to a loose pulley. A single means or control part serves in one operation for uncoupling the power and adjusting the brake device so that the lugs coöperate to bring about a prompt yet comparatively easy and shockless stoppage in which invariably the stitching mechanism or other parts of the machine will be brought to rest in a predetermined position or point.

At the right extremity of the main shaft 25 10 is a hand wheel 22. Near the hand wheel is a loose belt pulley 23 adjacent to a fast belt pulley 24, which, for convenience, may be formed in one part with a drum 25 secured upon it, so as to rotate with the main shaft. 30 A belt shifter 28 serves to couple or uncouple power from the main shaft, this being mounted at the end of a sliding rod 29 which is continually pressed toward the right by spring 30, tending to normally hold the belt 35 on the loose pulley. The spring 30 presses on a collar 31 on the slide 29 and the collar is engaged by the lower end of a swinging arm 32 downwardly projecting from shaft 33 which, at the front of the machine, has 40 a second arm 34 extending horizontally to where it is provided with a handle 35 or a treadle rod 36, or both. By now depressing the treadle rod or handle the arm 32 is swung to the left and the belt shifted to the 45 fast pulley, the release of the handle or treadle again restoring the belt to the loose pulley.

Associated with the main shaft, or rather with the drum 25 forming a portion thereof, is a brake device 40 which may be of various construction but is preferably as hereinafter described. This brake device is shiftable endwise of the shaft between its inoperative position to the left and its operative position to the right, in which latter it effects the braking of the drum and shaft in a manner the details of which will be hereinafter explained. The brake device 40 is bodily carried upon a slide or rod 41 supported in suitable guides or bearings. It is proposed to move the slide 41 with or by the slide 29 carrying the belt shifter and, although they could be rigidly connected for this purpose, it is preferred that the arm 42 45 46 shall actuate them both. Thus a stud 42

is shown on arm 32 engaging a side recess in slide 41. By this arrangement the brake device and belt shifter may be moved to the right or to the left in unison and the belt shifter given a greater extent of movement than the brake device. In effect the arm 32 and the parts which serve to move it constitute a single means for both uncoupling the power and shifting the brake device endwise into operative position, and vice 70 75 versa.

The brake device 40 is shown as comprising a brake shoe or band 45 extending nearly around the periphery of the drum 25. The drum, it will be noted, is wider than the 80 band so as to permit endwise adjustment of the latter without disengagement of the parts.

It should be explained that in all of the figures the parts are shown in their position 85 when the machine is stopped.

The brake device is provided with an extension 46 reaching around oppositely to the brake band 45 and overlapping the latter at a point where the two are connected by a 90 slot connection 47 permitting the slight relative play necessary for the tightening of the band.

The contacts or lugs may be as follows: The brake band is provided with a contact 95 lug 48 extending laterally rightward from the band. The drum 25 is provided with an outwardly extending stop lug 49 adapted to strike the lug 48 when the lugs are in registry so as to tighten the band for braking the 100 drum. The drum is also provided with a check lug 50 for checking any tendency to rebound, so that, when stopped, the parts are brought quite definitely to a predetermined position.

Figs. 5, 6, and 7 show more particularly the construction of the drum and lugs carried thereby. The drum is partitioned into two recesses by web 55 connecting the rim of the drum to its hub 56, which latter is 110 pinned to the shaft 10. The lug 49, which is intended to yield upon the impact in stopping the machine, is formed or mounted upon a casting 60 in the form of a ring surrounding the hub 56. Thus is permitted a 115 limited play of the lug 49 in a slot 61 formed in the drum. The casting 60 is provided with an arm 62 normally engaging a stop 63 formed on the partition 55. A strongly compressed coil spring 64 is located between 120 arm 62 and a stop 65 so as to resist the yielding of the lug 49 and, to increase the resistance a second such spring 66 is located between the lug 49 and the stop 63. The check lug 50 has a slight play in a slot 70 125 in the drum. This lug is carried on an arm 71 capable of swinging radially and provided with a pin 72 determining its outward position as more clearly seen in Fig. 5. The arm 71 is pivoted to a block 73 which ex- 130

tends through an aperture 74 in the partition 55 so that the check lug may receive guidance from the other side of the partition as seen in Fig. 7. Referring to Fig. 5, 5 a spring 75 is employed to hold the check lug arm 71 in the position shown. Referring to Fig. 7, the block 73 is shown carried upon a casting 76 having a ring form and surrounding the hub 56. This arrangement 10 permits circumferential movement of the check lug in addition to the radial swinging movement of its arm 71. The circumferential movement is resisted by a strong spring 77 located between the block 73 and 15 the stop 65. It will be understood that the lugs 49 and 50 are in registry with each other and that the lug 48 on the brake band is out of registry with lugs 49 and 50 when the machine is running, but in registry with them 20 when the machine is to be stopped. The fittings of the check lug 50 are such as to permit its depression into the drum as the lug 48 relatively rides over it so that the lugs 48 and 49 may meet, the lug 50 resuming its 25 illustrated position and serving to yieldingly check rebound.

The operation of the machine may be as follows: The parts are shown in stopped position. To restart the machine the arm 35 30 or treadle rod 36 is depressed. This swings the arm 32 to the left compressing the spring 30 and sliding the slides 29 and 41 to the left. The leftward movement of slide 41 shifts the brake band device to the left, carrying the lug 48 out of registry with the lugs 49 and 50, so that the brake device is 35 rendered inoperative. The brake band is sufficiently stout so that the ordinary light friction which may occur between it and 40 the drum is unable to tighten the band, and the drum is left to run freely. The slide 29 couples the power by shifting the belt to the fast pulley 24. Thereupon the machine commences running at full speed. The stoppage 45 is effected by releasing the handle 35 or rod 36. The spring 30 thereupon swings the arm 32 to the right shifting the belt to the loose pulley and at the same time shifting the slide 41 to the right, which carries with it the brake band, moving the 50 brake band lug 48 into registry with the lugs 49 and 50. Immediately the fast moving lug 49 on the drum strikes the brake band lug 48, two things occur. The impact 55 serves to tighten the brake band for slowing down the drum. At the same time the momentum carries the drum farther, with the result of compressing the springs 64 and 66 which, as they are compressed, serve to increase 60 the pressure of lug 49 on lug 48 so as to progressively increase the braking force of the band upon the drum. In this way the momentum of the parts is utilized 65 to effect their own stoppage with a progressive braking action and accompanied by a

yielding which avoids shock. The stoppage is peculiarly easy, effective and prompt. As soon as the parts have come to rest the springs 64, 66 reassert themselves to the slight extent necessary to restore the parts 70 to the position shown. These reverse movements are practically insignificant. To prevent any excessive reverse movement or rebound, the check lug 50 comes into play. This lug had been depressed into the drum 75 by the lug 48 in the act of stopping but it immediately springs out to the positions shown in Figs. 5 and 6, so that the lug 48 is confined between the lugs 49 and 50 and improper movements prevented as desired. 80 In connection with the stopping and starting operations described, a certain control of a presser-foot is attainable when the invention is applied on a sewing machine. Thus the hub 80 of the swinging presser-foot lifting arm 17 is mounted at the inner end of the slide 41 which carries the brake device 40. A slotted connection 81 is shown permitting the arm to swing yet compelling it to move endwise with the slide. In the 85 adjustment shown the arm 17 has its stud 19 in operative position so that the cam 20 has lifted the presser-foot with the stoppage of the machine. When the machine is restarted by moving the slides 29 and 41 to the left, the hub 80 and arm 17 are also moved to the left thus carrying the stud 19 to inoperative position whereby the lifting cam 20 has no effect upon it during the 90 running of the machine. It will thus be seen that a single means has been provided for uncoupling the power, applying the 95 braking device and causing the automatic lifting of the presser-foot upon the stoppage of the machine, and in restarting restoring all of these parts to their previous 100 position.

It will thus be seen that there has been described a stop mechanism embodying the features and attaining the objects and advantages referred to and further advantages will be apparent to those skilled in the art. Since many matters of arrangement, design, detail and other features may be varied without departing from the principles hereof, no limitation to such features is intended excepting so far as specified in the appended claims.

What is claimed is:

1. In combination, a rotary shaft having a drum portion, a brake device adjacent said drum comprising a shoe and an impact stop lug on the shoe, a stop lug carried by the drum, means for adjusting said device endwise of the shaft to bring the lugs into 120 or out of registry, and a check lug carried by and projecting from the rotary drum in alignment with the stop lug and capable of depression into the drum interior by the shoe lug riding over it.

2. In combination, a rotary shaft having a drum portion, a brake device adjacent said drum comprising a shoe and an impact stop lug on the shoe, a stop lug carried by the drum, means for adjusting said device endwise of the shaft to bring the lugs into or out of registry, and a check lug carried by and projecting from the rotary drum in alignment with the stop lug and capable of depression into the drum interior by the shoe lug riding over it and of yielding upon a rebound of the drum.
3. In combination, a rotary shaft having a drum portion, a brake device adjacent said drum comprising a shoe and an impact stop lug on the shoe, a stop lug carried by the drum, a loose belt pulley adjacent the drum and a single means for shifting a belt from and to the drum to and from the loose pulley, and for adjusting said device endwise of the shaft to bring the lugs into or out of registry, whereby the shaft will be slowed by said brake band and positively stopped by said lugs.
4. In combination, a rotary shaft carrying a drum and an impact stop lug, a brake

device comprising a shoe and an operating lug which also serves as an impact stop lug, a slide substantially parallel to said shaft carrying the brake device, and means for shifting the slide to bring the lugs into registry, whereby the shaft applies its own brake and said lugs give a positive final stop.

5. In combination, a rotary shaft carrying a drum and an impact stop lug, a brake device comprising a shoe and an operating lug which also serves as an impact stop lug, a slide substantially parallel to said shaft carrying the brake device, a power uncoupler, and a single means for operating said uncoupler and for shifting the slide to bring the lugs into registry, whereby the shaft applies its own brake and said lugs give a positive final stop.

In testimony whereof we affix our signatures in presence of two witnesses.

JOHN KIEWICZ.
FRANK ZALESKI.
